NAPHTHA GASIFIER OR VAPORIZER

Vincenzo Colombo and Gino Olivari, Milan, Italy,
assignors to Gassificatore Lampo Società
Anonima, Rome, Italy

Application May 2, 1934, Serial No. 723,442
In Italy May 17, 1933

1 Claim. (Cl. 123—127)

This invention relates to naphtha vaporizers or gasifiers as used for internal combustion engines and of the kind which allows the engine to be started on a light fuel and afterwards to work with a heavier fuel.

With a view to increasing the heating surface, the vaporizing chamber is, in the case of known naphtha vaporizers, usually made in the shape of a labyrinth, but that arrangement involves considerable pressure losses.

The present invention provides a naphtha vaporizer which avoids these pressure losses because it uses a vaporizing chamber which is essentially rectilinear and because the consequently diminished surface is increased by corrugating the walls of the vaporizing chamber.

A further improvement in the heating of the vaporizer is attained, according to the present invention, because the pipe for conveying away the hot exhaust gases is combined in a single block with the vaporizing chamber and with the induction chamber; the effect of the heat thus accumulated, is that the starting up of the engine on gasoline is expedited and, moreover, the naphtha in its turn is more fully utilized.

One form of construction of the vaporizer according to the present invention, is shown by way of example upon the annexed drawing, in which:—

Fig. 1 is a longitudinal section of the vaporizer, Fig. 2 is a sectional plan, and Fig. 3 is a cross-section on the line III—III of Fig. 2.

Referring to Fig. 1, provision is made at the inlet 10 for a three-way cock, by the aid of which the engine can be started up on gasoline and after the engine has once been started, the fuel-feed is changed over to naphtha.

In the first stage, the valve 2 remains open and the valve 1 is closed (dotted line position). A combustible mixture of gasoline and air is in this case supplied through a jet or nozzle (not shown) at 12 and passes by the valve 2 into the suction or induction chamber 3. After having been heated in this chamber 3, the mixture passes through the induction pipes 4 and 5 directly into the corresponding engine-cylinder, the compressed charge being thereafter exploded in the usual way.

In a second working stage, the valve 2 is closed and the valve 1 is opened by the actuation of a lever (not shown) whereby the supply of gasoline is shut off and at the same time a passage is afforded for the mixture of naphtha and air coming from a mixing jet or nozzle located at 11. This mixture is, however, thoroughly vaporized

in the vaporizing chamber 6 which is itself heated externally by the exhaust gases in the outer casing or chamber 9, and the mixture then passes through the elbow-shaped passage 7, the pipe 8 and the valve 1 at 10 into the suction chamber 3. Thence, as described for the first stage, it is drawn through the induction pipes 4 and 5 into the corresponding engine cylinder.

The very rapid resumption of the vaporization of the naphtha after a stoppage of the engine due to voluntary or other interruption of working, is attained by the absence of all external feed pipes and by the incorporation of the three chambers 6, 3 and 9 in a single heat-accumulating block.

The induction pipes 4 and 5 are connected directly to the cylinder block. The exhaust gases from the engine enter the outer chamber or casing 9 at 13 and after heating the corrugated chamber 6 located inside the outer chamber 9, escape at 14.

The outer casing or chamber 9 is provided with a removable lid or cover which is not shown in Figure 1, and the end of the chamber 9 is provided with the detachable cover plate 15. The end walls of the suction chamber 3 as seen in Figure 1, are connected by webs 16 to the corrugated lower wall of the vaporizing chamber 6.

What we claim is:

A naphtha vaporizer for an internal combustion engine, comprising in a single block an outer casing, means for passing exhaust gases from the engine into and from said casing, a rectilinear vaporizing chamber located inside said outer casing, said vaporizing chamber having corrugated walls, a suction chamber also arranged inside said outer casing and between said outer casing and the corrugated wall of the said vaporizing chamber, said suction chamber communicating with the inner ends of induction pipes leading to the cylinder block, communicating passages between said vaporizing chamber and said suction chamber, means for supplying gasoline mixture directly to said suction chamber and means for supplying naphtha mixture to said vaporizing chamber.
